US00D677299S

(12) **United States Design Patent**
Sheppard et al.

(10) **Patent No.:** US D677,299 S
(45) **Date of Patent:** ** Mar. 5, 2013

(54) **ELECTRONIC DEVICE**

(75) Inventors: **Nasahn Adam Sheppard**, Mill Valley, CA (US); **Maarten Dinger**, San Francisco, CA (US); **Shannon Colleen Fong**, San Francisco, CA (US); **Peter Michaelian**, Tappan, NY (US); **John Furlan**, Belmont, CA (US); **Jonathan Kaplan**, San Francisco, CA (US); **Ariel Braunstein**, San Francisco, CA (US); **Simon Fleming-Wood**, Oakland, CA (US); **Elizabeth A. Cleary**, San Francisco, CA (US)

(73) Assignee: **Cisco Technology, Inc.**, San Jose, CA (US)

(**) Term: **14 Years**

(21) Appl. No.: **29/376,666**

(22) Filed: **Oct. 8, 2010**

Related U.S. Application Data

(63) Continuation of application No. 29/345,075, filed on Oct. 8, 2009, now Pat. No. Des. 627,380.

(51) **LOC (9) Cl.** **16-05**

(52) **U.S. Cl.** **D16/219; D16/202**

(57) **CLAIM**

The ornamental design for an electronic device, as shown and described.

DESCRIPTION

FIG. 1 is a top, front and left side perspective view of an electronic showing our new design;

FIG. 2 is a top, rear and left side perspective view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front elevational view thereof; and,

FIG. 8 is a rear elevational view thereof.

The portions of the electronic device in broken lines are shown to illustrate environment only and form no part of the claimed design.

1 Claim, 6 Drawing Sheets
